ABSTRACT

A pulse waveform recognition circuit includes an input stage consisting of a tuned circuit tuned to approximately the frequency of a sinusoid to half-waves of which the pulses to be recognized approximate. A transistor is biased to conduct weakly and has its base coupled to the tuned circuit so as to be turned on by a pulse within the band width of the tuned circuit. The transistor drives a monostable multi-vibrator with a frequency dependent feedback circuit which causes the reversion time of the multi-vibrator to decrease as the frequency of triggering increases and which also increases the threshold voltage required to trigger the monostable circuit as this frequency increases. The circuit is used in an ignition system for an i.c. engine.

**CIRCUIT FOR RECOGNIZING A PULSE
WAVEFORM AND AN IGNITION SYSTEM FOR
AN I.C. ENGINE INCLUDING SUCH A CIRCUIT**

This invention relates to a circuit for recognising a pulse waveform of unipolar shape approximating to a half wave sinusoid. It is one object of the invention to provide such a circuit which is capable of rejecting spurious signals.

A circuit in accordance with one aspect of the invention comprises an input stage consisting of a damped tuned circuit tuned to resonate at a frequency approximately equal to the frequency of the sinusoid to which the pulse waveform to be recognised approximate, semi-conductor amplifier means, coupling means coupling the tuned circuit to the amplifier means, and a bias circuit for the amplifier means biasing the amplifier means to a state in which it is almost non-conducting.

The invention also relates to ignition systems for i.c. engines utilizing a magnetic pick-up device driven by the engine to trigger ignition. It is another object of the invention to provide an ignition system in a convenient form.

In accordance with this aspect of the invention an i.c. engine ignition system includes a magnetic pick-up device driven by the engine and producing a train of pulses of unipolar shape approximating to a half wave sinusoid together with spurious signals, a pulse recognition circuit comprising an input stage which forms in combination with the pick-up a damped tuned circuit tuned to resonate at a frequency approximately equal to the frequency of said sinusoid, semi-conductor amplifier means, coupling means coupling said tuned circuit to the amplifier means and a bias circuit biasing the amplifier means to a state in which it is almost non-conducting, said amplifier means being rendered conductive by each pulse from the pick-up device, and an ignition control circuit connected to be triggered by the amplifier means to produce a spark whenever a pulse is produced by the pick-up device.

In the accompanying drawings

FIG. 1 is the circuit diagram of an example of an i.c. engine ignition system in accordance with the invention,

FIG. 2 is a fragmentary perspective view of a pick-up which is used in the ignition system,

FIG. 3 is the circuit diagram of a different form of pulse waveform recognition circuit which could be incorporated in place of that used in FIG. 1 and

FIG. 4 is a graph showing waveforms at various points in the circuit of FIG. 3.

Referring firstly to FIGS. 1 and 2 the system shown includes a magnetic pick-up including a winding L which is arranged so that its axis is parallel to the rotary axis of a rotor 10 of a non-magnetic material. Set in the edge of the rotor 10 are a plurality (one for each engine cylinder) of magnetic bistable wire elements 11 which also have their axes parallel to the rotary axis of the rotor 10. The winding 11 is mounted on a carrier 12 on which there are carried two pairs of magnets 13, 14, 15, 16, the pair 13, 14 being arranged on one side of the winding L and the pair 15, 16 being arranged on the other. As the wire 11 approaches the carrier 10 it is magnetized in one direction by the magnets 13, 14 (if it is not already magnetized in that direction). The wire then passes close to the winding L and whilst it is close to the winding it comes into the magnet field of the

magnets 15, 16 which reverse the magnetization of the wire. This reversal of the magnetisation of the wire occurs whilst the winding L is in the magnetic field of the wire, so that a voltage pulse of short duration and approximately half wave sinusoid form is induced in the winding L. The amplitude of this pulse is an order of magnitude greater than the amplitude of any voltage induced by variable reluctance effects, but various other electrical interference may be present which will superimpose other waveforms on the output of the winding and the output of the winding L may typically be as shown in the upper-most trace in FIG. 4. The width of each pulse is relatively independent on the speed of rotation of the rotor 10, typically varying by only $\pm 25\%$ over the normal engine speed range.

It will be appreciated that the rotor 10 may take the place of the cam in a conventional contact breaker/distributor assembly, the carrier 12 being mounted on the conventional contact carrier, so that normal vacuum/speed advance and retard action is obtained.

The circuit shown in FIG. 1 is intended to recognize the half wave sinusoid pulse produced by the pick-up winding L but to ignore electrical noise and other interference.

To this end the circuit includes as an input stage a resistor R₁ and a Capacitor C₁ forming in combination with the winding L a sub-critically damped tuned circuit which resonates at a frequency the half-period of which is approximately equal to the mean pulse length emitted by the winding L. One side of the capacitor C₁ is connected to an earth rail 17 and the capacitor is bridged by two parallel reverse connected diodes D₁ and D₂ one of which serves to limit the voltage which can exist across the capacitor C₁ and the other of which is provided for protection against reverse polarity connection of the circuit to the battery B,

The other side of the capacitor is coupled via a diode connected n-p-n transistor D₃ to the base of an n-p-n transistor T₁. The base and collector of the transistor D₃ are connected together and by a resistor R₂ to a rail 18 which is in turn connected to a regulated supply 19 powered via a rail 20 from the battery B. The voltage on the rail 18 is a multiple of the base-emitter voltage of a transistor included in the regulated supply 19 so that it fluctuates with temperature in the same manner as other semi-conductor component parameters in the circuit.

The bases of the two transistors D₃ and T₁ are connected together and the emitter of the transistor D₃ is connected to said other side of the capacitor C₁. The collector of the transistor T₁ is connected to the rail 18 via a resistor R₃ and the emitter of the transistor T₁ is connected to the common point of a low-impedance resistance chain R₄, R₅. The ratio of R₄ and R₅ is chosen so that, in the absence of a pulse from the winding L, the voltage at their common point is less than the forward breakdown voltage of the diode D₂ and the resistor R₂ is chosen so that the transistor T₁ conducts only very weakly. The transistor D₁ also conducts weakly via the resistor R₁ and the winding L. The transistors D₃ and T₁ operate as a transconductance amplifier.

When the winding L produces a pulse the voltage waveform appearing at the emitter of transistor D₃ is a smoothed version of the voltage waveform of the output of the winding except that at the end of the pulse the voltage on the capacitor C₁ will reverse because the tuned circuit of which it forms part is sub-critically damped. Whilst the forward voltage exists the transistor T₁ is biased to conduct more strongly so that the voltage

at the emitter of transistor T_1 tends to follow the voltage at the emitter of the transistor D_3 . When the voltage on the capacitor C_1 reverses the transistor T_1 turns off completely.

The collector of the transistor T_1 is also connected to the cathode of a diode D_4 , the anode of which is connected to the common point of a higher impedance resistance chain R_6, R_7 . The collector of the transistor T_1 is furthermore connected to the cathode of a diode D_5 with its anode connected by a yet higher impedance resistor R_8 to the rail 18. A capacitor C_2 has one side connected to the anode of the diode D_5 and the other side connected via a resistor R_9 to the rail 18.

Said other side of the capacitor C_2 is also connected to the base of an n-p-n transistor T_2 the emitter of which is connected to the rail 17 and the collector of which is connected via a resistor R_{10} to the rail 20. The collector of the transistor T_2 is connected to the base of an n-p-n transistor T_3 and also to the cathode of a protective diode D_6 , the emitter of the transistor T_3 being connected to the rail 17 and its collector being connected to the rail 18 by a resistor R_{11} . The collector of the transistor T_3 is connected to the cathode of a diode D_7 which has its anode connected to the anode of the diode D_5 .

The transistors T_2 and T_3 and their associated components act as a monostable multi-vibrator in the stable state of which the transistor T_2 conducts and the transistor T_3 is non-conductive. When a negative-going trigger pulse is applied via the diode D_5 the transistor T_2 turns off, turning on the transistor T_3 thereby providing positive feedback via the capacitor C_2 until this is fully charged when the circuit reverts to its stable state. At low frequency the reversion time is constant but at higher frequency the reversion time decreases and the mark-to-space ratio tends towards the ratio $R_9:R_8$ as the frequency increases.

In order to turn off the transistor T_2 the transistor T_1 must draw sufficient current to take substantially all the current from the resistor R_9 (this is speed invariant), current from resistors R_3 and R_8 (this is speed dependent since the current will depend on the state of charge of the capacitor C_2) and the current from the diode D_4 (this too is speed dependent). The net result is that the voltage at the emitter of the transistor D_1 required to trigger the monostable increases with frequency — i.e., with engine speed. This lessens the risk of the circuit being spuriously triggered as a result of increasing voltage output from the coil L resulting from the variable reluctance effect mentioned above as distinct from the increasing pulse amplitude at higher speeds.

The collector of the transistor T_3 is connected via a resistor R_{12} to the base of an n-p-n output transistor T_4 which has its emitter connected to the rail 17 and its collector connected via a resistor R_{13} to the rail 20. A protective diode is connected between the base and emitter of the transistor T_4 which acts as an inverting buffer. A capacitor C_3 is connected between the collector of the transistor T_4 and the rail 17 and the output of the circuit is taken from the collector of transistor T_4 via a resistor R_{14} .

Thus, when each pulse is produced by the pick-up, there is a positive-going pulse produced by the transistor T_4 of duration corresponding to the reversion time of the monostable circuit mentioned above. This pulse is fed to an ignition power amplifier circuit 21 which may include a step-up transformer arranged so that a spark occurs at the spark plug 22 when the negative-going output pulse appears.

Turning now to FIG. 3 the circuit includes an input stage consisting of a subcritically damped tuned circuit made up of an inductor L^1 which is part of a pick-up similar to that shown in FIG. 1, a resistor R_{21} and a capacitor C_{21} in a series circuit. The value of the capacitor C_{21} is so chosen in relation to the inductor L^1 that the circuit is tuned to resonate at a frequency approximately equal to the frequency of the sinusoid to which the half waves to be recognized approximate. The resistor R_{21} is so chosen that the damping of the circuit is just subcritical. The waveform which is produced by the transducer (i.e., across the inductor L^1) is shown in the upper trace of FIG. 4. As shown the waveform includes pulses of approximately half wave sinusoidal form upon which a great deal of higher frequency noise is superimposed.

The second trace of FIG. 4 shows the voltage which actually appears across the capacitor C_{21} . The broken line indicates how the voltage across the capacitor C_{21} is unloaded by the transistor Q_{21} and the solid line the actual waveform in the circuit shown in FIG. 3. It will be observed that the high frequency noise has been substantially suppressed. This results from the fact that the impedance of the capacitor C_{21} is very low compared with that of the inductor L^1 and the resistor R_{21} to inductively introduced noise. Similarly any spurious high frequency signals introduced capacitively into the circuit via the lead connecting the inductor L^1 to the resistor R_{21} are also suppressed since the impedance of C_{21} will be much lower than the impedance of the stray capacitance coupling these signals into the lead.

The input stage described is a.c. coupled by a capacitor C_{22} to the base of n-p-n transistor Q_{21} which has its emitter grounded and the collector of which is connected to the cathode of a diode D_{21} the anode of which is connected by a resistor R_{22} to a positive supply rail 30. The transistor Q_{22} has a bias circuit constituted by a pair of resistors R_{23}, R_{24} in series between the rail 30 and the base of the transistor Q_{21} , a diode D_{22} with its anode connected to the interconnection of the resistors R_{23}, R_{24} and its cathode grounded, and a resistor R_{25} connecting the base of the transistor Q_{21} to earth. These components are so selected that the transistor Q_{21} is just conductive, the diode D_{22} tending to hold the base voltage too low for substantial conduction.

The third trace of FIG. 4 shows the voltage applied to the base of the transistor Q_{21} which draws current from the tuned circuit and therefore accounts for the drop in peak voltage. The final trace shows the current flow through the collector of the transistor Q_{21} . The sharp rectangular waveform obtained is obtained without any feedback and results from the high gain of the transistor configuration.

It will be noted that, because the tuned circuit is subcritically damped, the voltage across C_{21} as shown in FIG. 4 (second trace) becomes negative briefly immediately after the receipt of the input pulse. This negative voltage is rectified by the base-emitter diode of the transistor Q_{21} and the negative voltage is stored on the capacitor C_{22} which discharges slowly through the resistor R_{25} and through the resistor R_{24} . This effect is indicated by the third trace of FIG. 4 which shows the base voltage on the transistor Q_{21} . As a result the transistor Q_{21} is reversed biased for the time between receiving pulses and this assists in preventing triggering of the circuit by spurious signals.

The remainder of the circuit acts as a monostable circuit for pulse prolongation and a buffer. An n-p-n transistor Q_{22} has its base directly coupled to the collec-

tor of the transistor Q_{21} , its emitter being grounded and its collector being connected to the rail 30 via a resistor R_{26} and to ground via a resistor R_{27} . The collector of the transistor Q_{22} is also connected to the base of an n-p-n transistor Q_{23} which has its emitter grounded and its collector connected to the rail 30 by a resistor R_{28} . The collectors of the transistors Q_{21} and Q_{23} are interconnected by a resistor R_{29} and the collector of the transistor Q_{23} is connected to the cathode of a diode D_{23} which has its anode connected to the rail 30 by a resistor R_{30} . A capacitor C_{23} interconnects the anode of the diodes D_{21} and D_{23} .

The buffer stage is constituted by an n-p-n transistor Q_{24} with its base coupled by a resistor R_{31} to the collector of the transistor Q_{23} . The emitter of the transistor Q_{24} is grounded and its collector is connected to the rail 30 by a resistor R_{32} . The collector of the transistor Q_{24} is also connected to ground by a capacitor C_{24} and connected to the output terminal 31 by a resistor R_{33} . A capacitor C_{25} is connected between the supply rail 30 and ground.

Although the circuit described can be used in an ignition system it can also be used for many other applications, particularly where it is required to determine the position of a rotating or linearly movable member accurately.

I claim:

1. In combination, a magnetic transducer comprising an inductor and magnetic means for inducing in the inductor periodically a pulse waveform of unipolar shape approximating to a half wave sinusoid, and a recognition circuit including a capacitor and resistor in series with the inductor and forming a damped tuned circuit tuned to resonate at a frequency approximately equal to the frequency of the sinusoid to which the pulse waveform to be recognized approximates, semiconductor amplifier means having an input across which the capacitor is connected, coupling means coupling the tuned circuit to the amplifier means and a bias circuit for the amplifier means biasing the amplifier means to a state in which it is almost non-conducting.

2. A circuit as claimed in claim 1 in which the coupling means is a coupling capacitor and the biasing means includes a diode connected to that when the voltage of the capacitor of the tuned circuit reverses following a pulse applied thereto the amplifier means is reversed biased for a period.

3. A circuit as claimed in either claim 1 in which the amplifier means is a transistor forming part of a transconductance amplifier.

4. A circuit as claimed in claim 3 including a monostable circuit connected to be driven out of its stable state when said transistor becomes conductive.

5. A circuit as claimed in claim 1 in which said damped tuned circuit is a subcritically damped tuned circuit.

10 6. A circuit as claimed in claim 1 in which said magnetic means includes a length of bistable magnetic wire and magnetic polarizing means acting on said wire to reverse the magnetization thereof whilst the wire is magnetically coupled to the inductor.

15 7. A circuit for recognizing a pulse waveform of unipolar shape approximating to a half wave sinusoid, said circuit comprising an input stage consisting of a damped tuned circuit tuned to resonate at a frequency approximately equal to the frequency of the sinusoid to which the pulse waveform to be recognized approximates, semi-conductor amplifier means, coupling means coupling the tuned circuit to the amplifier means and a bias circuit for the amplifier means biasing the amplifier means to a state in which it is almost non-conducting, and in which the amplifier means is a transistor forming part of a transconductance amplifier and the transistor has its base connected to the base and collector of a diode connected transistor, the bases being connected via a resistor to one of a pair of supply rails, the emitter of the diode connected transistor being connected to the other supply rail via a d.c. path through said tuned circuit, and the emitter of said transistor being connected to the common point of a low impedance resistance chain connected between said rails.

30 8. A circuit as claimed in claim 7 including a monostable circuit connected to be driven out of its stable state when said transistor becomes conductive.

35 9. A circuit as claimed in claim 8 wherein the monostable circuit includes a frequency dependent feedback circuit whereby the reversion time of the monostable circuit reduces as the frequency of triggering thereof increases.

40 10. A circuit as claimed in claim 9 in which said frequency dependent feedback circuit is connected to vary the bias on said transistor so that the output voltage from the tuned circuit required to trigger the monostable circuit increases as the frequency of operation increases.
